UNITED STATES PATENT OFFICE.

HENRY G. BARNHURST, OF ALLENTOWN, PENNSYLVANIA, ASSIGNOR TO FULLER
ENGINEERING COMPANY, A CORPORATION OF PENNSYLVANIA.

BURNING PULVERIZED FUEL.

1,382,712.

Specification of Letters Patent. Patented June 28, 1921.

Application filed June 26, 1918. Serial No. 242,099.

To all whom it may concern:

Be it known that I, HENRY G. BARNHURST, a citizen of the United States, residing at Allentown, in the county of Lehigh, State of

5 Pennsylvania, have invented certain new and useful Improvements in Burning Pulverized Fuel; and I do hereby declare the following to be a full, clear, and exact description of the invention, such as will enable 10 others skilled in the art to which it appertains to make and use the same.

This invention relates to the combustion of pulverized coal in the furnaces of stationary boilers.

15 It has long been recognized that by the use of coal in pulverized form, many distinct and most valuable advantages are to be obtained. The feed of the coal can be regulated to a nicety just as the feed of oil and 20 gas is so regulated. The intensity of the combustion is subject to absolute control because it depends directly upon the percentage of air mixed with the coal. Losses are reduced by beginning the feed of the fuel 25 when heat is required and discontinuing it instantly when heat is no longer needed.

There is a complete elimination of the losses incident to the use of lump coal due to the formation of clinkers which prevent the un- 30 burned coal around the clinkers from receiving the proper amount of air. Stack losses may be reduced as it is unnecessary to use so large a percentage of excess air.

There need be no loss of fuel in the ash, all 35 of the combustible being completely consumed. Pulverized coal produces little or no smoke. With pulverized coal, the maximum of flexibility is attained permitting quick adjustment to suit any condition of 40 underload and overload; in case of accident, the fuel supply may be cut off instantly and for installations to meet many, if not all, requirements, the initial cost of the necessary apparatus is less.

45 These pronounced advantages which are to be attained by using coal in pulverized rather than lump form, together with the marked success which has attended the use of pulverized coal in cement kilns and metallurgical apparatus, have led to many attempts to burn pulverized coal in the furnaces of stationary boilers. So far as I am aware, such efforts have not been commercially successful, so that prior to the present 50 invention, pulverized coal has not been used

in the furnaces of stationary boilers for any substantial period of time with results that compare at all favorably with those obtained by using coal in lump form.

I have found that the requisite of success 60 in burning pulverized coal in the furnaces of stationary boilers which workers in this art have heretofore failed to recognize, is the necessity for properly proportioning the furnace with reference to the velocity of 65 travel of the hot gases through the furnace. Failures due to such improper proportioning of the furnace have been the more frequent because so many efforts to use pulverized coal have been made by employing furnaces originally designed and built for the use of lump coal. In those cases, the velocity of travel of the hot gases of combustion has been far too high. The high temperature existing within the furnace during 70 the burning of the pulverized coal reduces the refractory lining to a more or less plastic condition and in this condition, a high velocity of the flow of the furnace gases results in erosion which soon amounts to destruction. 75

I have discovered that pulverized coal may be used in the furnaces of stationary boilers whose walls are lined with refractory material, economically as compared with the results obtained in using lump coal and successfully overcoming the difficulties heretofore experienced, by so proportioning the furnace as to produce a greatly reduced velocity of flow of the gases of combustion 80 through the furnace. The cross-sectional area of the furnace transverse to the direction of travel of the hot gases must be large in proportion to the air and coal admitted so as to keep the velocity of flow of the gases 85 below that which will produce erosion of the refractory lining of the walls of the furnace, and in computing the velocity of the gases, care must be exercised to make adequate allowance for the very considerable expansion 90 of the air admitted with the fuel which occurs when the temperature of the air is raised by the combustion of the fuel. I have found in the course of extended experimentation that to insure successful operation and 95 eliminate the danger of destruction of the refractories, the velocity of travel of the gases of combustion through the furnace to the heat-absorbing surfaces of the boiler 100 should not be in excess of seven feet per sec- 105

ond and that a velocity of approximately five feet per second is productive of the best results. The importance of the velocity of travel of the gases through the furnace is 5 greatest at the point in their travel at which the highest temperature is reached. The refractories in the walls of the furnace about that portion where the highest temperature is reached are softened the most, and therefore 10 most subjected to erosion. The point at which this highest temperature is reached will vary with several factors notably the character of the fuel being burned, but will always be a substantial distance short of 15 the water-tubes or other heat-absorbing surfaces for considerable heat is absorbed from the gases with resultant contraction thereof before the gases actually reach the tubes.

Low velocity of the travel of the gases of 20 combustion through the furnace is also of advantage in connection with the action of the ash. When in operation, ash is deposited upon the furnace walls, building up thereon in a flocculent state and forming a protective covering for the refractory material. As 25 this protective covering of ash increases in thickness, particles or lumps of it break off and fall into the ash pit of the furnace and thereafter new deposits are gradually formed 30 at such points. If the velocity of the travel of the gases were high, as it has been under prior practice, such deposited ash and also the material of the refractories would be eroded by the high speed of travel of the gases. 35 Moreover, the movement of the gases at low velocity affords a greater opportunity for the particles of ash to settle through the space within the furnace and collect in the ash pit.

40 The distance through which the pulverized fuel travels from the point of ignition to the heat-absorbing surfaces should be great enough to insure complete combustion of all of the combustible contained in the 45 fuel before the heat-absorbing surfaces are reached. In this connection, it is to be borne in mind that the volatile constituents of the coal burn with comparative rapidity, that the fixed carbon takes a longer time 50 to ignite and that the highest temperatures are developed in the zone where the fixed carbon is consumed. The distance of travel from the point of ignition of the fuel to the heat-absorbing surfaces should be great 55 enough to insure that the consumption of the fixed carbon will be substantially complete before the heat-absorbing surfaces are reached. This consideration has been appreciated heretofore and in some instances special provision has been made for lengthening 60 the path of travel of the combustible and the hot gases developed thereby from the point of ignition of the fuel to the boiler tubes, as for instance by causing the hot

gases to follow a course which is more or less 65 of a loop.

The principles of the present invention may be appreciated more accurately by considering their application to conditions which are met in actual engineering practice. 70 For example, consider the case of a 600 horse power boiler operating at 150% rating to produce 900 boiler horse power. In order to produce unit boiler horse power, 34.5 pounds of water must be evaporated per hour and 75 therefore the production of the desired 900 horse power would require that 31,050 pounds of water be evaporated per hour. If we assume that the coal used has a heat value of 13,500 B. T. U. when fired in dry pulverized condition, and that an efficiency of 77% 80 can be obtained, then, as the latent heat of vaporization is 970.4 B. T. U., 1 pound of coal will evaporate 10.71 pounds of water. And in order to evaporate the 31,050 pounds 85 of water per hour required to produce the 900 boiler horse power, it would be necessary to burn 2899 pounds of coal per hour. This amounts to 48 pounds of coal per minute and allowing for 5% of ash in the coal, the total 90 of the combustible fired per minute would be 45.8 pounds.

The combustion of 1 pound of carbon requires that approximately 154 cubic feet of air be mixed with the carbon to supply the 95 requisite amount of oxygen. It is common practice, however, to mix with the carbon in the coal a greater proportion of air in order to increase the proportion of carbon dioxide and correspondingly decrease the proportion 100 of carbon monoxide in the gases of combustion. A 20% excess of air over the amount required for theoretically perfect combustion of the carbon in the coal, amounting to 105 180 cubic feet of air for each pound of combustible, is a proportion which is commonly employed in the effort to produce a relatively large amount of carbon dioxide, as for instance 17%. Assuming that this 20% excess or 180 cubic feet of air be admitted with 110 each pound of combustible, the theoretical temperature within the furnace would be substantially in excess of 3000° F., but a considerable allowance must be made for radiation and other losses, and making such allowance, the temperature reached within the furnace would be approximately 2,600° F. With this as the temperature within the furnace, it is possible to compute the volume to 115 which the air admitted to the furnace expands as its temperature is increased. Bearing in mind that gases expand in direct proportion to changes in their absolute temperature, the incoming air at 50° F. in being raised to a temperature of 2600° F. will increase in volume to six times its original volume. Therefore, the air admitted to the furnace at the rate of 180 cubic feet of air 120

for each of the 45.8 pounds of combustible, expanded to six times its initial volume, would produce 49,464 cubic feet of hot gases passing through the furnace per minute, or 5 824 cubic feet per second. In order that these gases may not flow through the furnace at a velocity in excess of seven feet per second, the furnace would have to be designed so as to have a cross-sectional area 10 transverse to the direction of travel of the gases at a point where the highest temperature is reached of at least 118 square feet, and if it were of square cross-section it would have to be approximately 11 feet 15 square. Preferably the velocity of travel of the hot gases is reduced somewhat below seven feet per second. In practice I have found that with a velocity of the hot gases equal to 5.5 feet per second, excellent results 20 may be obtained, and in the example discussed this velocity would require that the furnace be approximately 150 square feet in section transverse to the direction of travel of the gases, or about 12 feet on a side in the 25 case of a furnace of square cross-section.

As a guide in designing furnaces for stationary boilers for the use of pulverized coal, it is convenient to adopt as a rule that the furnace should be designed to have 40 cubic 30 feet of volume for each pound of combustible to be burned per minute. Applying this rule to the example discussed, the furnace should have a volume of 1832 cubic feet, which in the case of a furnace which is 35 a perfect cube, would require that the furnace be about 12 $\frac{1}{4}$ feet on a side and would give a velocity of travel of the gases of combustion of approximately 5.5 feet per second. This rule is, of course, subject to variation 40 as the design of the furnace departs from that of a perfect cube as it is the cross-sectional area transverse to the travel of the gases of combustion rather than the cubical contents of the furnace which is 45 important.

I have annexed hereto drawings illustrating boilers having furnaces lined with refractory material and designed for the use of coal in pulverized form in accordance 50 with the present invention. In these drawings Figure 1 illustrates a boiler of the Babcock & Wilcox type and Fig. 2 illustrates a boiler of the Stirling type, both figures being longitudinal cross-sections.

55 Referring to Fig. 1, the furnace of the boiler has a front wall 10, rear wall 11, side walls 12, floor 13, cleaning openings 14 and arch 15. The hot gases of combustion flow through a passage 17 to the water tubes 18 connected by headers 19 and the usual pipes to drums 20, baffle plates 21 being provided 60 to guide the gases in their flow among the tubes into the chamber 22 leading to the stack. The pulverized coal is stored in a 65 hopper 23 and is fed by a feeder 24 into a

tube 25 through which it passes by gravity into a burner nozzle 26 projecting into an opening in the front wall of the furnace. A blower 27 is connected to the nozzle 28 to produce a current of air therethrough carrying the pulverized fuel into the furnace and additional air may be entrained and carried into the furnace, the amount of this additional air being subject to the control of regulating valves 29 and 30. It will be 70 noted that the furnace is approximately a cube. In accordance with this invention, it is so proportioned with reference to the air and combustible fed into the furnace for the production of the desired boiler horse 75 power as to keep the velocity of flow of the hot gases at the point where the highest temperature is reached down to seven feet per second. By reason of this reduced velocity of flow of the hot gases, the refractory lining of the furnace will not be subjected to erosion to any substantial extent and the apparatus may be used over a considerable period of time.

In connection with the construction shown 90 in Fig. 1, it is to be noted that the cross-section of the passage 17 leading from the furnace proper to the heat-absorbing surfaces 18 is not necessarily the cross-sectional area which determines the maximum velocity 95 of flow of the hot gases for the reason that the temperature of the gases in this passage 17 may be considerably less than the temperature existing below the passage and within the furnace proper. This is due to 100 the proximity of the gases in the passage 17 to the heat-absorbing surfaces 18; the water in tubes 18 absorbs heat from the gases to a substantial extent before the gases come in actual contact with the tubes or reach 105 the spaces between the tubes, and as the gases in the passage 17 give up their heat to the water in the tubes 18 there is a considerable reduction in their volume which offsets the effect of the smaller cross-section 110 at the passage 17 upon the velocity of travel of the gases. Thus, in a boiler installation of the type hereinabove discussed operating under such conditions that the temperature within the furnace proper is 2600° F., the 115 temperature in the passage leading to the water tubes may be as low as 1800° or 2000° F. by reason of the absorption of heat by the water in the tubes and the fact that the walls of the furnace close to the elements of 120 the boiler proper are kept at a lower temperature.

In Fig. 2, the mechanism for supplying pulverized coal and air to the furnace is substantially the same as that illustrated in 125 Fig. 1. The shape of the furnace is somewhat different and the tubes 36, drums 37 and baffles 38 of the boiler are differently arranged, the arrangement being that which is usual in boilers of the Stirling type. 130

Here again the furnace is so shaped with reference to the air and fuel admitted to the furnace for the production of the desired boiler horse power as to keep the 5 velocity of travel of the hot gases down to or below seven feet per second.

In the constructions illustrated in Figs. 1 and 2, the time of travel of the fuel from the point of ignition to the heat-absorbing 10 surfaces is great enough to insure that the fuel will be entirely consumed before the heat-absorbing surfaces are reached, thus avoiding injury to the water tubes, waste of heat and the production of smoke. The decreased 15 velocity of travel of the fuel and hot gases through the furnace, resulting in an increase in the time of passage through the furnace, simplifies the matter of providing for complete consumption of the fuel 20 within the furnace. The time required for the consumption of the fuel varies with a number of factors, particularly the degree of fineness to which the pulverized fuel is ground. The larger the particles of fuel, 25 the greater will be the time required for their consumption. It would be difficult to formulate a rule governing the length of the path for the fuel and gases through the furnace sufficient to insure complete combustion 30 before the gases reach the heat-absorbing surfaces, but, generally speaking, the reduction of the velocity of flow of the hot gases in accordance with this invention to such a point as will eliminate the destruction 35 of the refractories by erosion, increases the time of travel through the furnace to such extent as will insure complete combustion of the fuel.

In the drawings annexed hereto illustrating 40 constructions which may be employed in the practice of the invention, it must be understood that these constructions are merely typical of constructions which may be employed, and, except for the relative proportions of the parts, they are constructions which have been commonly used in 45 this art heretofore.

It is further to be understood that while the invention has been described with reference to the use of pulverized coal only, it 50 is not limited in this respect as it may be employed in connection with the use of any pulverized carbonaceous fuel substance, including lignite, culm, etc.

I claim:

1. The method of utilizing pulverized fuel in a stationary boiler having a furnace lined with refractory material which consists in introducing pulverized fuel and air into the furnace and igniting the mixture 60 thereof within the furnace, maintaining the supply of fuel and air to the furnace substantially continuously to maintain continuous combustion within the furnace, and causing the deflagrating fuel and the gases of 65 combustion to flow through the furnace at low velocity such that at the point in the travel of the gases through the furnace at which the highest temperature is reached the velocity will be substantially seven feet 70 per second, to substantially avoid erosion of the refractory walls of the furnace and insure that combustion of the fuel will be complete within the furnace.

2. The method of utilizing pulverized 75 fuel in a stationary boiler having a furnace lined with refractory material which consists in introducing pulverized fuel and air into the furnace and igniting the mixture thereof within the furnace, maintaining the 80 supply of fuel and air to the furnace substantially continuously to maintain continuous combustion within the furnace, and causing the deflagrating fuel and the gases of combustion to flow through the furnace 85 with a velocity which, at the point in the travel of the gases at which the highest temperature is reached, is less than seven feet per second, to substantially avoid erosion 90 of the refractory walls of the furnace and insure that combustion of the fuel will be complete within the furnace.

In testimony whereof I affix my signature.
HENRY G. BARNHURST.
